CLAIM

The ornamental design for a canine fingers puppet, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyrights whatsoever.

FIG. 1 is an illustration of a back view of the canine fingers puppet embodying my new design;

FIG. 2 is an illustration of a front view of the canine fingers puppet embodying my new design;

FIG. 3 is an illustration of a left side view of the canine fingers puppet embodying my new design;

FIG. 4 is an illustration of a right side view of the canine fingers puppet embodying my new design;

FIG. 5 is an illustration of a top view of the canine fingers puppet embodying my new design;

FIG. 6 is an illustration of a bottom view of the canine fingers puppet embodying my new design; and,

FIGS. 7-10 are illustrations of the back, front, left right, top and bottom views thereof, showing the design in use.

The broken line showing of the hand in FIGS. 7-10 is for illustrative purposes only, and forms no part of the claimed design.
